(57) **CLAIM**

The ornamental design for light emitting diodes on a printed circuit board, as shown and described.

DESCRIPTION

FIG. 1 is a perspective view of a pattern and orientation of LEDs of the present disclosure;

FIG. 2 is a front view of the pattern and orientation of LEDs of FIG. 1;

FIG. 3 is a rear view of the pattern and orientation of LEDs of FIG. 1;

FIG. 4 is a right side view of the pattern and orientation of LEDs of FIG. 1;

FIG. 5 is a left side view of the pattern and orientation of LEDs of FIG. 1;

FIG. 6 is a top view of the pattern and orientation of LEDs of FIG. 1; and,

FIG. 7 is a bottom view of the pattern and orientation of LEDs of FIG. 1.

The broken lines of FIGS. 1-7 are provided for purposes of illustration and form no part of the claimed design of the present application.
